UNITED STATES PATENT OFFICE.

CHARLES HOUGHTON, OF BOSTON, MASSACHUSETTS.

IMPROVEMENT IN WATER-ELEVATORS.

Specification forming part of Letters Patent No. 124,209, dated March 5, 1872.

To all whom it may concern:

Be it known that I, CHARLES HOUGHTON, of Boston, in the county of Suffolk and State of Massachusetts, have invented an Improvement in Water-Elevators; and I do hereby declare that the following, taken in connection with the drawing which accompanies and forms part of this specification, is a description of my invention sufficient to enable those skilled in the art to practice it.

a denotes a hollow and tight receptacle, alternately for water and steam, said receptacle being preferably made in the form of an elongated cylinder, of any suitable material, and of a size and length adapted to the amount of water to be raised, and the steam, which can be produced in the same generator, hereinafter mentioned. Its length should be proportioned to its diameter, about as nine to one. It must be of sufficient strength to sustain without injury several times the pressure of the column of water to be raised. *b* is the inlet-pipe, which conducts the water to be raised from the well or cistern into the upper part of the cylinder *a*. Within the cylinder this pipe should be perforated, so as not to hold water when there is none in the cylinder around it. In this inlet-pipe, just below or at the bottom of the cylinder *a*, I place a box or trap, or make a bend in the pipe, as shown at *n*. This will be more fully described hereafter. *c* is a valve in the inlet-pipe, below the cylinder *a*, the valve being made, for greater certainty of operation, with two gates and gate-seats, the gates operating independently of each other. A leakage at this valve would stop the action of the apparatus, but with the double-gated valve it is made very certain that no leakage can occur. All the valves used in this elevator, hereinafter described, are made, preferably, with double gates and seats, for the reason stated. The gates in the valve *c* open upward, to admit the flow of water from the well through the inlet-pipe *b*, and close by their own gravity when water ceases to flow upward, thus preventing the water above the valve from flowing back to the well or cistern. *d* is the outlet-pipe, from near the bottom of the cylinder *a*, to the top, or near the top of the injection-chamber *e*, conducting the water raised into the injection-chamber, and also conducting steam, (as hereinafter described,) when all the water in the cylinder *a* above its outlet-pipe, has passed up.

This pipe should be of suitable material, (preferably metal not easily softened by heat,) and of inside diameter sufficient to allow the water to flow without much friction, and as rapidly as it is desirable to deliver it into the tank above. The outlet-pipe *f* is taken from the lower part of the injection-chamber *e*, (leaving space enough between it and the bottom of the injection-chamber to contain as much water as is needed for the supply to the steam-generator, and to condense the steam in the cylinder *a*,) and thence is continued to the tank where the water is to be stored. This continuation of the outlet-pipe from the injection-chamber is marked *f*. The injection-chamber *e* is a hollow tight vessel, of copper or other suitable material, of about one-quarter the inside capacity of the cylinder *a*, above, and, preferably, directly over which it is placed, it being intended to contain a portion of air in its upper part, while its lower part will usually contain water. At times, both the air and water may be displaced by steam. Into the upper part of the chamber *e* the outlet-pipe *d* (from the cylinder *a*) discharges water and steam alternately. From the bottom of the chamber *e* a water-pipe is taken, which pipe, in case the steam-generator is supplied from this chamber, conducts water to it, and also to the cylinder *a* for condensation, as hereinafter described. This chamber I call the injection-chamber, its purpose being to retain water sufficient for the supply of the steam-generator, and to condense the steam in the cylinder *a* at the proper time, the steam from the cylinder *a* entering it through the outlet-pipe *d*, and combining with, and by its heat expanding, the air which will accumulate there, liberating the water and aiding, and, to some extent, forcing the water in its descent and entrance into the steam-generator and cylinder. The continuation *f* of the outlet-pipe taken from the chamber *e*, and a little way from the bottom, and thence leading where the water raised is to be stored for use, is made of any suitable material, and any desirable size, and contains a valve, *g*. This valve *g* in the outlet-pipe is a double-gated and double-seated valve, placed at any convenient point between the injection-chamber *e* and the tank where the water is to be delivered, its purpose being to prevent any return of the water which has once passed it, and to prevent the ingress of

air, also, through the pipe *f*. *h* is the steam-pipe leading from the steam-generator *m* to the top of and into the cylinder *a*, and of suitable size and strength to conduct steam from the generator. In a small elevator for house use, three-eighths to one-half inch diameter will be more satisfactory than a larger pipe. *i* is a water-pipe (of about the same size as the steam-pipe just described) for conducting water from the injection-chamber *e* to the cylinder *a*, for the purpose of condensing the steam in the cylinder when it has driven all the water out to and through the injection-chamber *e*. It is taken from the bottom of the injection-chamber and carried downward some distance, preferably below the bottom of the cylinder *a*, and thence turned upward and entered into the cylinder *a* at or near its top. When the supply of water for the steam-generator is taken from the injection-chamber, this condense water is preferably taken from the water-supply pipe, as shown in Fig. 2. The double-gated and double-seated valve *j* is placed in the condense-water pipe, in its upward turn, opening upward and toward its opening into the cylinder *a*. Its purpose is to prevent the water or steam from the cylinder *a* from passing through this pipe toward the injection-chamber or steam-generator. *k* is the water-supply pipe, its purpose being to supply the steam-generator *m* with water, intermittently, between the movements of the water from the cylinder *a*, upward, to replenish what has been evaporated. In Figure 1 this pipe is shown as taken from the bottom of the cylinder *a*; thence carried downward some distance, as may be convenient for the insertion of the valves described; thence horizontally toward the steam-generator; thence perpendicularly to and into it. In the perpendicular parts of this water-supply pipe are placed the valves *l* and *l'*, as described. In this adaptation of the water-supply pipe, it is desirable that it should be somewhat larger when it is taken from the injection-chamber, being preferably one and a half to two inches in diameter.

In large-sized elevators, I deem this arrangement preferable to the other described; but for ordinary house use, this water-supply pipe may, and probably should, generally be taken from the injection-chamber *e*, as shown in Fig. 2. From thence it will be carried down some distance below the level of the bottom of the steam-generator *m*, thence horizontally toward it, and thence perpendicularly to and into the bottom or lower part of it.

l is a valve in the perpendicular part of the water-supply-pipe, next to and entering into the steam-generator, the valve being double-gated and opening upward toward the opening into the steam-generator, and closing downward by its own gravity when water ceases to flow past it. Its purpose is to prevent the passage of water or steam from the steam-generator through the water-supply pipe *k* toward the cylinder *a*, or the injection-

chamber *e*. *l'* is a valve in the water-passage, between the cylinder *a* and the steam-generator *m*, in its perpendicular part, next to and opening into the cylinder *a*. It is double-gated, and its purpose is to prevent the passage of water or steam from the cylinder *a* through the pipe *k* to the steam-generator, except intermittently, at the periods when it is necessary to replenish the water in the steam-generator. At such time it is opened by its connection with the pan *o*, which will be hereinafter described, and its operation explained. The gates of this valve are connected to each other by a chain or its equivalent, arranged with a little slack between them, so that when the upper gate is raised it will ascend a little distance, say one-sixteenth of an inch, before the lower gate moves to follow it.

The steam-generator *m* is made of metal of suitable strength and tenacity, and of such inside capacity for water as may be sufficient to generate steam to expel all the water from the cylinder *a*, without converting more than one-third to one-half the water in it into steam. The form of this steam-generator is not important, beyond its adaptation to creating steam with a moderate expenditure of fuel.

If the elevator is to be operated by a fire for cooking or other purposes, the generator is so shaped as to perform its own work without interfering with or impeding the other operations carried on by the fire. In a cooking-range, the ordinary hot-water back, in many cases, may be used for a generator. For this apparatus, when it is so used, the usual hot-water boiler must be detached from it and connected with a pipe running through the fire-pot in front of the hot-water back, and returning back close up under the top plate of the range or stove. A three-quarter inch pipe used in this way will heat the water in the boiler satisfactorily. Experience has shown that it is not advisable, though it is possible to heat the water in the hot-water boiler, and operate the elevator by the same generator or heater.

o is a metallic pan pivoted and balanced by the lever *p* and connection *q*, connecting it with the valve *l'*. When the water in the cylinder descends past the pan *o*, water remains in the pan, and its weight overbalances the weight of the lever *p*, connection *q*, and valve *l'*, and it descends with the water in the cylinder and raises the valves *l'* from their seats, and opens a passage for the water from the cylinder through the pipe *k*, to supply the steam-generator. The water in the cylinder being higher than in the generator, and the pressure of the steam being the same in both, the water finds its level and fills the steam-generator. When the cylinder is filled again from the well, the lever *p*, connection *q*, and valves *l'*, being heavier than the pan *o* when immersed in water, the valve-gates *l'* descend again by their own gravity and close the passage.

Fig. 3 is a top view (enlarged) of the cylin-

der *a*, water-pan *o*, inlet-pipe *b*, lever *p*, water-supply pipe *k*, and valve *l*. *n* is a trap in the inlet-pipe, made by putting in a box, or by a bend in the pipe, its purpose being to keep a body of water in the pipe at all times to prevent the escape of steam from the cylinder *a*, down the inlet-pipe, in case the valves should leak and let the water out of the cylinder *a*. In such case, if the leak was not discovered, and the fire was kept up, the elevator would cease to operate, and the water in the steam-generator and the injection-chamber would be, after a while, all converted into steam, and pass down the pipe *b*, and there condense and run down to the well or cistern. Then the steam-generator would be burned and destroyed. But, with this arrangement, if the valve leaks and all the water in the cylinder runs down, there will still be left water in the steam-generator and the injection-chamber, and as fast as this is converted into steam—it being prevented by water in the trap *n* from going down the inlet-pipe—the steam will go up the outlet-pipe into the injection-chamber, and will be condensed there and return through the water-supply-pipe to the steam-generator, so that the water in the generator would not be exhausted or diminished, even though a fire should be kept up for several days, when the elevator was taking up no water from below, the steam-generator being thus preserved; whereas without this device, it would certainly be burned out in a very short time. *r* is a safety-valve, which may be placed upon the steam-generator or steam-pipe, and weighted sufficiently to remain closed against all the ordinary operations of the elevator; but to open, if, by any accident or cause whatever, the outlet-pipe should become obstructed, in such case yielding and opening before the parts of the elevator would be broken or injured by pressure of steam. Frost in the outlet-pipe might produce an explosion if the safety-valve were not employed. *s* is a cock, to admit air into the steam-pipe, if it should at any time be desirable to do so. Said cock extends downward from the under side of the highest part of the steam-pipe, and contains a plug by which it can be closed entirely, and a valve opening upward, and in the end a plug, which is pierced with a very fine hole. It will be perceived that, if the cock be left open when steam is condensed in the cylinder the air will go through the opening in the plug and fill the steam-pipe with air, and, perhaps, extend into the cylinder. This arrangement of the air-cock with the check-valve placed beneath the pipe and opening upward, is shown in section in Fig. 4. *t* is an arrangement of a funnel-pipe and cock on the top of the injection-chamber, for the purpose of introducing water to start the apparatus.

The whole apparatus, being constructed as described and made perfectly tight, and strong enough to be durable, operates as follows: To start it, enough water is introduced into the injection-chamber to fill or nearly fill the steam-generator, and it is not necessary to fill any

of the other parts, although it is well enough to do so if it is perfectly convenient. The steam-generator being filled with water, or nearly so—the cylinder and pipes containing air only—steam is generated and passes along the pipe *h* to the cylinder *a*, and expels the air it contains up through the outlet-pipe *d*, and then from the injection-chamber up through the outlet-pipe *f*. When the steam has expelled all the air, and is passing freely up the pipe *f*, past the valve *g*, the water, which up to this time, has remained in the water-supply pipe and condense-pipe and injection-chamber, if any was left there, will flow through the water-supply pipe *k*, and enter the steam-generator, cooling that and the water in it, operating as a steam cut-off; and instantly, after flowing through the condense-pipe *i*, it will condense the steam in the cylinder *a*, and, producing a vacuum, cause a flow of water from the well or cistern to fill it. The first operation will not always fill the cylinder quite full of water, but a few operations will do so or nearly so. In the ordinary operation of this apparatus, there will at all times be a small quantity of air in the top of the cylinder *a* and in the top of the injection-chamber, and this will gradually accumulate from the air introduced with the water, and unless discharged, might, in a little while, fill the cylinder; but, when the accumulation of air becomes too great, so as to occupy a space equal to a quarter of the cylinder, or thereabouts, it discharges and clears itself of air by its own operation. After the first operation, as described, the steam generated acts directly against the water in the cylinder without any intermediate, except the layer of air which will always be there in a larger or smaller quantity, and pressing against the surface forces it up the outlet-pipe *d* into the injection-chamber *e*, filling that as full as the air in the upper part of it will permit it to be filled with water. When the air in the injection-chamber is compressed in the top of the chamber, as much as the weight of the column of water above it will compress it, then water flows into the tank where it is to be stored, and each operation will deposit a uniform quantity there, equal to the contents of the cylinder *a*, less the amount necessary to replenish the steam-generator and start the condensation in the cylinder *a*. When the steam has expelled the water from the cylinder *a* it follows it up the outlet-pipe *d*, to and into the top of the injection-chamber *e*, and mingling with the air there, heats and consequently expands it, liberating the water in the chamber, and, in fact, forcing it—although it might flow by its own gravity—through the water-supply-pipe into the steam-generator, stopping the generation of steam and replenishing the water evaporated from it. As soon as the generation of steam has ceased, in fact, simultaneously with it, the water from the injection-chamber *e*, flows through the condense water-pipe, and falling into the steam in the cylinder *a* condenses it, producing a vacuum, and the cylinder is again

filled from the well. If any more air is desirable in the apparatus than is brought in with the water, it can be admitted at pleasure, by opening the cock *s*. The fire being kept up so as to produce steam, the operation of the apparatus will continue, as described, and will cease only when the fire goes down. If more water is raised than the tank above will contain, a waste-pipe must be provided to return the surplus to the source from which it was taken, or otherwise dispose of it. In case the outlet-pipe should become obstructed by frost or otherwise, the safety-valve *r* will be weighted so as to open before any breakage of the steam-generator cylinder, or any of the connecting pipes will take place. In case of leak in the valve of the inlet-pipe, so that the water in the cylinder falls back, there will still remain a portion of the water in the air-chamber and steam-generator, which will be converted into steam, and as the water in the device *n* will prevent the steam going down the inlet-pipe, and condensing there, and then escaping it will ascend to the injection-chamber and be condensed there, and thence return to the steam-generator, again to be reconverted into steam, and again circulate, thus maintaining in the steam-generator a sufficient supply of water to prevent its being burned out, or to save it from cracking when an additional supply of cold water is introduced. The difficulty which has heretofore existed in the liability of the steam-generator to get empty, in consequence of leakage of valves, and when empty to be burned out, or get hot and crack, when water flowed in again, is by the arrangement of parts here described, wholly obviated. If there should be no air in the upper part of the injection-chamber, the steam passing up the outlet-pipe *d* will alone liberate the water, and cause its flow through the water-supply and condense-pipes.

I claim—

1. In a water-elevator, operating substantially as described, the water-pipe extending from the bottom of the cylinder, or near it, to the steam-generator, when provided with a self-acting valve, arranged to permit flow of water from the cylinder to the generator, and to prevent return thereof.
2. The pan *o*, lever *p*, and connection *q*, as described, or a float operating to open and close the valve or cock *l*, substantially as described.
3. The double-gated and double-seated valves, arranged as described, in combination with an automatic water-elevator mechanism.
4. The cock *s*, for admitting air when a vacuum is wholly or partially formed in the apparatus, when combined with a check-valve opening inwardly to prevent outward flow from the apparatus when cock *s* is open.
5. The safety-valve *r*, in combination with an automatic water-elevator, as and for the purpose set forth, when the same is made automatic, in the manner described, and the steam-generator is replenished with water automatically and intermittently, as described.
6. The arrangement of the injection-chamber *e* with an automatic steam water-elevator and its steam-generator, water-supply, and condense-pipes, when the same is made to operate automatically, in the manner described, to cut off steam in and replenish the water evaporated from the steam-generator, and to inject water into the cylinder to condense steam therein.
7. In combination with the cylinder *a* of a water-elevator, the trap or bend described, located below the valve *c*, and arranged to operate substantially as and for the purpose set forth.

CHS. HOUGHTON.
